CLAIM

(73) Assignee: **Zalman Tech Co., Ltd**, Kyungki-do (KR)

I claim the ornamental design for a radiator for heat generating components in electronic equipment, as shown and described.

(**) Term: **14 Years**

(21) Appl. No.: **29/143,009**

DESCRIPTION

(22) Filed: **Jun. 7, 2001**

FIG. 1 is a perspective view of a radiator for heat generating components in electronic equipment according to the present invention.

(30) **Foreign Application Priority Data**

FIG. 2 is a front view of a radiator for heat generating components in electronic equipment according to the present invention, the rear view being a mirror image thereof;

Dec. 12, 2000 (KR) 2000-31737

FIG. 3 is a right side view of a radiator for heat generating components in electronic equipment according to the present invention, the left side view being a mirror image thereof;

(51) LOC (7) Cl. **13-03**

FIG. 4 is a top plan view of a radiator for heat generating components in electronic equipment according to the present invention.

(52) U.S. Cl. **D13/179**

FIG. 5 is a bottom plan view of a radiator for heat generating components in electronic equipment according to the present invention; and,

(58) Field of Search D13/179; 165/80.3

FIG. 6 is an exploded view showing the environment in which the design is used.

165/180, 185; 174/16.3, 706, 707, 718,
719, 720, 721, 722, 727, 686; 361/271,
274.3, 697, 702, 704, 709, 710, 711

The broken line showing of the environment is for illustrative purpose only and forms not part of the claimed design.
